UNITED STATES PATENT OFFICE.

ARCHIBALD W. JUSTICE, OF NEW YORK, N. Y.

PAINTBRUSH HOLDER.

Application filed October 18, 1926, Serial No. 142,437. Renewed December 1, 1928.

This invention relates to improvements in paint brush holders.

The primary object of the invention resides in a holder for attachment to the peripheral edge of a paint can for supporting a paint brush within a can in spaced relation to the walls of the can for preventing the handle of the brush from contacting with the side walls, and for preventing the brush from sinking into the can and becoming covered with paint.

Another object of the invention is to provide a holder for paint brushes which includes a hook for engagement with the peripheral edge of a paint can, and spring pressed jaws for gripping the handle of the paint brush for supporting the same vertically within the can.

A further object is the provision of a paint brush holder which is simple in construction, inexpensive of manufacture and efficient for the purpose intended.

With these and other objects in view, the invention resides in certain novel construction and combination and arrangement of parts, the essential features of which are hereinafter fully described, are particularly pointed out in the appended claim, and are illustrated in the accompanying drawing, in which:—

Figure 1 is a perspective view of my improved brush holder in position upon a paint can.

Figure 2 is a top plan view.

Figure 3 is a perspective view of the parts in separated position.

Referring more particularly to the drawing, the reference numeral 10 designates my improved paint brush holder in its entirety and which includes a pair of co-acting parts 11 and 12, each part being constructed of a single piece of flat bendable material.

The part 11 comprises a manipulating portion 13, an offset jaw 14 on one of its ends and a reduced connecting leg 15 between the portion 13 and the jaw 14. The other end of the material from which the part is constructed is twisted and bent to provide a hook 16 which serves as a supporting means for the holder. The part is notched inwardly from its opposite edges as at 17 for a purpose to be presently explained.

The part 12 is somewhat similar to the part

11 and comprises a manipulating portion 18, an offset jaw 19 on one of its ends, and a reduced connecting leg 20. When in assembled position, the reduced portions 15 and 20 cross each other so as to dispose the jaws 14 and 19 on the same horizontal plane. The other end of the material from which the part 12 is formed is provided with spaced opposed lugs 21 for reception in the notches 17 and which co-act with the walls of the notches for hingedly connecting the two parts together.

An expandable spring 22 is seated between the manipulating portions 13 and 18 for normally holding the jaws 14 and 19 in clamping position, with the toothed ends 23 of the jaws in engagement with each other. For expanding the jaws, it is only necessary to press inwardly upon the manipulating portions 13 and 18.

In practice, the holder is supported upon the peripheral edge of the paint can 24 by engaging the hook 16 therewith, as shown in Figures 1 and 2 of the drawing so that the jaws are disposed in spaced relation to the inner walls of the can. In order to support the paint brush 25 in a vertical position within the can and in spaced relation to the side walls thereof, the manipulating portions 13 and 18 are pressed inwardly against the action of the spring to spread the jaws a sufficient distance to receive the handle of the brush. Upon the release of the manipulating portions, the spring automatically closes the jaws about the handle and supports the brush in a vertical position.

It will be seen that my invention is capable of supporting a paint brush within a paint can so that the handle of the brush is prevented from contact with the side walls of the can, and from dropping to the bottom of the can when not in use, thereby keeping the handle of the brush free from paint. It will be appreciated that heretofore, it has been the practice of painters to rest the brush against the side walls of the can when not in use or place the brush across the top of the can, which usually results in soiling of the brush handle, due to the contact with the paint on the sides of the can. With my improved holder, it is possible to eliminate these objections.

What is claimed as new is:—
A paint brush holder comprising a pair of

separable parts, co-acting means on said parts for hingedly connecting the same together, each of said parts being constructed of a flat piece of bendable material and bent to provide co-acting clamping jaws, an expansion spring interposed between said parts for holding said jaws in clamping position, and a hook

bent from the material of one of said parts for engagement with the edge of a paint can for supporting the holder thereon.

10

In testimony whereof I hereby affix my signature.

ARCHIBALD W. JUSTICE.
